UNITED STATES PATENT OFFICE.

CHARLES H. WILLSON, OF MEDFORD, ASSIGNOR TO JAMES W. BROOKS, OF PETERSHAM, AND FRANK F. STANLEY, OF SWAMPSCOTT, MASSACHUSETTS, TRUSTEES.

DESIGN FOR A NAIL OR SLUG.

SPECIFICATION forming part of Design No. 25,086, dated January 21, 1896.

Application filed December 18, 1895. Serial No. 572,609. Term of patent 3½ years.

To all whom it may concern:

Be it known that I, CHARLES H. WILLSON, of Medford, county of Middlesex, and State of Massachusetts, have invented and produced 5 a certain new and useful Design for a Nail or Slug, of which the following is a specification, reference being had to the accompanying drawings, forming a part thereof.

Figure 1 of the drawings is an isometric 10 view of a nail or slug illustrating my design, and Fig. 2 is an end view thereof.

The leading feature of my design consists 15 in a nail or slug having its longitudinal edges rounded to form two substantially cylindrical portions of different diameters, connected by a portion substantially lozenge-shaped in cross-section, and intersecting at its opposite longitudinal edges the two cylindrical portions.

The drawings show a nail or slug having its 20 longitudinal edges rounded to form a large cylindrical portion *a* and a smaller cylindrical portion *b*, connected by an intermediate portion *c*, substantially lozenge-shaped in cross-section, and intersecting the cylindrical portions at its opposite longitudinal edges, leaving thin portions *a'* and *b'*.

I claim—

The design for a nail or slug, substantially as set forth.

In testimony whereof I have signed my name to this specification in the presence of two subscribing witnesses.

CHARLES H. WILLSON.

Witnesses:

JOHN C. EDWARDS,
FREDERICK L. EMERY.
